[57] CLAIM

We claim the ornamental design for a Christmas tree stand with octahedron chamber, as shown and described.

DESCRIPTION

FIG. 1 is a perspective view of a Christmas tree stand with octahedron chamber showing our new design;

FIG. 2 is a top plan view thereof;

FIG. 3 is a front elevational view thereof, the rear view being identical;

FIG. 4 is a side elevational view thereof, the opposite side being identical;

FIG. 5 is a bottom plan view thereof;

FIG. 6 is a perspective view of a second embodiment of FIG. 1, the difference residing in the shape of the bottom plate; and,

FIG. 7 is a perspective view of a third embodiment of FIG. 1, the difference residing in the shape of the bottom plate.
